UNITED STATES PATENT OFFICE.

ROBERT E. KEMPER, OF RENSSELAER, NEW YORK.

SHEET-FEEDING MACHINE.

1,180,299.

Specification of Letters Patent. Patented Apr. 25, 1916.

Application filed June 23, 1915. Serial No. 35,753.

To all whom it may concern:

Be it known that I, ROBERT E. KEMPER, a citizen of the United States, residing at Rensselaer, in the county of Rensselaer and State of New York, have invented certain new and useful Improvements in Sheet-Feeding Machines; and I do hereby declare the following to be a full, clear, and exact description of the invention, such as will enable others skilled in the art to which it appertains to make and use the same.

My invention consists in the novel features hereinafter described reference being had to the accompanying drawings which show a form or embodiment of the invention selected by me for the purpose of illustrating the same, and the invention is fully disclosed in the following description and claims.

Referring to the said drawings: Figure 1 represents a right side elevation of the machine or embodiment of my invention which I have selected for the purposes of illustration. Fig. 2 is a left side elevation of the same. Fig. 3 is a top plan view of the same. Fig. 4 is an end elevation of the same. Fig. 5 is a vertical longitudinal sectional view of the machine taken on the line 5—5 of Fig. 3. Figs. 6, 7, and 8 are detail views of parts of the mechanism illustrating them in different positions.

The object of my invention is to provide mechanism for automatically feeding in rapid succession sheets of paper, or other like articles, to a printing press or for any other purpose.

In carrying out my invention I provide means for supporting sheets (or other articles) to be fed, preferably in a vertically disposed pile; mechanism is provided for combing or fanning out the uppermost sheets, the topmost sheet being combed out farther than the adjacent sheets; separating mechanism is provided for separating the topmost sheet, a dividing roller is provided which is adapted to be moved between the separated sheet and the remainder of the pile, and carry the separated sheet into engagement with a feed roller which, preferably, rotates continuously and delivers the sheet from the pile. Means are provided for securing the movement of the combing device into and out of operative engagement with the pile of sheets and for rotating the

always be at least sufficiently advanced, and mechanism is provided which is brought into operation by the advance of the second sheet to temporarily throw out of operation the comber, and also mechanism for feeding the pile of sheets toward the comber, for the purpose of preventing the over feeding of the individual sheets and the too rapid advance of the pile. Mechanism is also provided preferably in close proximity to the dividing roller for clamping the second sheet adjacent to the feed roller, that is to say, adjacent to the delivery end of the mechanism, so as to prevent the second sheet from being advanced by the withdrawal and delivery of the topmost sheet.

My invention also provides a bending and friction rod beneath which the sheets are fed and which serves as a bending point for the topmost sheet, also to hold the top sheet from sliding back on the pile under the influence of the separator or separators.

My invention also comprises other novel features hereinafter fully described and particularly pointed out in the claims.

In the embodiment of my invention which I have selected for purposes of illustration the various parts of the mechanism are supported by a main frame, 1, which conveniently comprises a pair of side plates connected by suitable transversely disposed parts and forming, with the connected and supported parts, a unitary structure which may be supported adjacent to or attached to a printing press or other mechanism to which the sheets are to be delivered in any desired or convenient manner.

I will proceed to describe the mechanical parts assembled in this embodiment of my invention as they are shown in the accompanying drawings, it being understood that the particular form of gearing, the particular shape and configuration of the parts, and other details of construction are not material to the invention, and may be departed from in other embodiments thereof.

2 represents a horizontally disposed feed table for supporting a pile of sheets (or other articles to be individually fed), the said table being supported upon horizontal brackets, 3—3, each of which is secured to a vertically disposed rack bar, 4, mounted in guides secured to the inner faces of the side frames. These rack bars are engaged by pinions, 5—5, on a shaft, 6, mounted in bear-

ings in the side frames and provided at one end, see Figs. 2 and 3, with a ratchet wheel, 7, which is engaged by a locking pawl, 8, and also by an actuating pawl, 9, pivoted to a short arm, 10, secured to a rock shaft, 11, extending across the machine. The rock shaft, 11, carries the "comber" for fanning or combing out the upper sheets of the pile, which consists in this instance of a rotary disk, 12, provided with a circular series of idle rolls, 13, the peripheries of which are adapted to engage the topmost sheet of the pile. The comber is supported on a shaft, 14, carried at the outer end of a frame, 15, which is rigidly but adjustably secured to the rock shaft, 11. Rotary motion is imparted to the comber in any suitable manner, for example, as herein shown, by a means of a sprocket chain, 16, passing around the sprocket wheel, 17, on a comber shaft and around a driving sprocket, 18, on the shaft, 20, which in this instance is the main driving shaft of the machine, and is conveniently provided with means for driving it, as for example, the driving wheel, 19, see Fig. 3. Means are provided for positively raising the comber out of operative relation with the pile of sheets, to facilitate the withdrawal of the topmost sheet, and for permitting it to descend into contact with the top sheet of the pile, in each cycle of operation of the machine, and in this instance, these motions are imparted by means of a cam, 21, which engages a friction roll, 22, on a lifting arm, 23, loosely mounted on a transversely disposed stationary shaft or stretcher bar, 24, which may be, for example, one of the transverse supports for the side frames, the upper end of said lifting arm being connected by a link, 25, with the comber frame, 15. The raising and lowering of the comber will obviously operate the pawl, 9, and ratchet wheel, 7, and effect a vertical movement of the feed table, 2. The driving mechanism which rotates the comber will also be so arranged as to impart to the comber ample movement when in contact with the top sheet of the pile to effect the feed of the topmost sheet to the desired point, as hereinafter described, and I prefer to so construct the mechanism that the feed of the comber will be rather in excess of than below the requirements of the machine and to provide means for automatically arresting the comber when the topmost sheets have been fed farther than necessary or desired, said mechanism to be controlled by the second sheet of the pile so that over feeding by the comber will be automatically prevented, and simultaneously with the arresting of the comber the vertical feed of the table, 2, will be arrested so as to prevent over feeding thereof. For the purpose of arresting the comber when in raised position and preventing its descent upon the

pile of sheets, I provide a stop arm, 26, mounted on a rock shaft, 27, and provided with a shoulder, 28, adapted to engage a shoulder or projection, 29, formed on or connected to the lifting arm, 23, so as to prevent the descent of said arm from its raised position when the stop arm is thrown into position to engage the stop or shoulder, 29, as hereinafter more fully explained.

In conjunction with the feed table, 2, I preferably provide a vertically disposed front guide in the form of a board or wall, 30, at the end of the feed table nearest the delivery end of the mechanism, which engages the front edges of the sheets of the pile, and I also prefer to provide laterally adjustable side guides, 31-31, which are conveniently secured to the cross shaft, 24, by set screws or otherwise, and are adjustable transversely of the machine, so as to engage the lateral edges of the sheets of the pile adjacent to the top of the pile, and prevent the sheets from becoming twisted. Extending rearwardly from the upper edge of the front guide, 30, I prefer to provide an upwardly inclined stationary board, 32, which supports the forwardly projecting portions of the fanned out or combed out upper sheets of the pile as clearly shown in Fig. 5 and the said feed board, 32, is given, preferably, such an inclination that the projecting portions of the said sheets will be slightly bent upward, although this is not essential. I prefer to provide adjacent to the upper end of the front guide, 30, a transversely extending bending and friction rod, 33, to engage the topmost sheet of the pile at some distance from its outer end for the purpose of forcing it to bend at this point, when it is engaged and actuated by the separator or separators as hereinafter described, and also to exert a light friction on the topmost sheet so that the topmost sheet cannot be moved backwardly over the pile, under the operation of the separator or separators. I prefer to have this rod adjustable both longitudinally of the sheets, that is to say, backwardly and forwardly in the machine, and also vertically in order that it may set at the most advantageous point with respect to the particular sheets which are being fed and, in this instance, I have shown the rod, 33, carried by two arms, 34, at opposite sides of the machine secured to the side plates by screws, 35, passing through slots in the arms, 34, thus providing for the adjustment of the rod vertically as well as longitudinally of the machine.

36 represents the feed roller which is preferably, although not necessarily, continuously rotated. The feed roller is mounted on a transversely disposed shaft, 37, and in this instance is driven by a sprocket chain, 38, passing around a sprocket wheel, 39, on the shaft, 37, and a

driving sprocket, 40, on the driving shaft, 20, although obviously other forms of gearing may be employed. I prefer to use a comparatively narrow feed roller, 36, although this is not important. To facilitate the delivery of the sheets singly from the apparatus, I prefer to provide a delivery roller, 41, at the rear end of the mechanism mounted on a shaft, 42, and driven in this instance from the shaft, 37, by means of a crossed belt, 43, and pulleys, 44 and 45, an idle roller 46 being supported with its shaft, 47, engaging vertically slotted or yoke shaped bearings, 48, so that the idle roller, 46, rests upon the delivery roller, 41, and is rotated thereby to feed the intervening sheet as the successive sheets are delivered.

Adjacent to the feed roller, 36, I provide separating mechanism for engaging the edge of the topmost sheet and bending it upwardly away from the inclined feed board, 32, and toward the feed roller, 36. For this purpose I employ one or more separators each of which comprises a vertically disposed but slightly inclined rod, 50, provided at its upper end with one or more teeth. I prefer to flatten the upper end of the separator into a sort of blade, and to provide it with a plurality of teeth, but this is not essential. In the drawings I have only shown one of these separators but it will be understood that I may use two, three, or any number which may be found most convenient and desirable. The separator is given a vertical movement and in this instance I have shown the lower end of the separator, 50, connected to an actuating arm, 51, adjustably secured to a rock shaft, 52, extending transversely of the machine, the upper end of the separator being guided in a slot or guide aperture in the feed board, 32, or provided with any other suitable form of guiding means. The rock shaft, 52, may be actuated in any desired manner. In this instance, I have shown it provided with an actuating arm, 53, see Fig. 2, to which is pivotally connected one end of a bar, 54, the other end of which is provided with a yoke portion, 55, having a guiding engagement with the driving shaft, 20, the said bar being provided with a friction roller, 56, engaging a cam, 57, on the driving shaft, 20, for moving the bar, 54, endwise and imparting movement to the rock shaft, 52, in one direction the parts being moved in the opposite direction by means of a spring, 58, in this instance, connected to the arm, 53, at 59 and to the frame at 60. By means of this construction the separator is moved downwardly by the cam, 57, and is moved upwardly to actuate the top sheet by the spring, 58, so that should it encounter any obstacles the separator will not be injured.

65 61 represents a dividing roller which is

adapted to be moved forward beneath the top sheet after it has been lifted by the separator or separators, to effectually divide it from the rest of the pile and also to move it into operative relation with the feed roller and cause it to be drawn off of the pile and delivered from the apparatus. This roller, 61, is carried by an oscillating frame. This frame comprises, in this instance, a vertically disposed bar or member, 62, the lower end of which is secured to a rock shaft, 63, and has a rearwardly extending portion, 64, at its upper end which carries the roller, 61. The rock shaft, 63, is provided at one end, see Figs. 1 and 4, 80 with an actuating arm, 65, to which is pivotally connected one end of a rod or bar, 66, the other end of which is provided with a forked portion, 67, having a guiding engagement with the main driving shaft, 20, 85 and provided with a friction roller, 68, engaging a cam, 69, on the driving shaft, 20, for moving the rod, 66, rock shaft, 63, and connected parts in one direction while a spring, 70, connected to the arm, 65, at one end and to the main frame at the other moves the rod, 66, and arm, 65, in the other direction, and moves the dividing roller toward and causes it to press the separated sheet against the feed roller with a yielding pressure; the cam, 69, controlling the movement of the roller under the action of said spring. I also provide means adjacent to the dividing roller and feed roller for clamping the forward end portions of the second sheet, preferably upon the feed board, while the top sheet is being drawn out in order to prevent the second and other sheets of the pile from being disturbed in the slightest degree by the drawing off of the top sheet. In this instance, I have shown a clamping jaw, 71, pivoted at 72 to the frame member, 62, and having its rear end curved at 73 to conform to the curvature of the periphery of the roller, 61, as shown in Fig. 6, so as to prevent any of the sheets from getting between the clamping jaw and the roller. The clamping jaw, 71, is held in elevated position by a retracting spring, 74, and is depressed into operative position by means of a pull rod, 75, the lower end of which passes through an aperture in a lever, 76, pivoted at 77 to the lower portion of the frame member, 62, the said rod being provided above the lever, 76, with a shoulder, 78, and with a shoulder, 79, at a distance below said lever and a coil spring, 80, being interposed between the shoulder, 79, and the lever, 76, so that the downward movement of the lever, exerts a yielding pull upon the clamping jaw, 71.

According to my invention after the top sheet has been raised by the separator or separators and the dividing roller, 61, has passed beneath the top sheet the separator

immediately descends, releasing the top sheet and immediately engaging the edge of the second sheet in readiness for the next cycle of the machine, and I conveniently 5 operate the clamping device from the rock shaft, 52, which in this instance is provided with an arm, 81, secured thereto in such position that when the rock shaft, 52, is moved by its cam, 57, in a direction to lower the 10 separator or separators into engagement with the second sheet, the arm, 81, will strike the lever, 76, as indicated in Figs. 7 and 8 and depress the clamping jaw, 71, upon the second sheet, thereby clamping it securely 15 to the feed board, 32, and holding it until the top sheet is withdrawn from the pile and delivered from the machine.

I have stated heretofore that means are provided according to my invention for 20 preventing the descent of the comber upon the pile of sheets and incidentally preventing the upward feed of the pile in case the sheets are fed forward too rapidly. This I accomplish by means entirely independent 25 of the delivery of the topmost sheet and which are actuated directly by the second sheet of the pile, and I am, therefore, enabled to secure a more perfect and positive and satisfactory operation of this mechanism 30 than would be the case if I depended upon the topmost sheet to actuate said mechanism. To this end I provide what I term a trigger which comprises a vertically disposed slender rod, 82, carried by the dividing roller frame member, 62, to which it is pivotally connected. In this instance, the member 62 is provided with a block, 83, adjustably secured thereto by means of a set screw and the trigger, 82, which is preferably 35 in the form of a bell-crank is pivoted at 84 to said block and has a short arm, 85, which engages a stop lug or stud, 86, and is provided with an upturned portion, 87. A very light spring 88 connected to the short 40 arm, 85, holds it normally against the stop lug, 86, and determines the position of the trigger, 82, with respect to the oscillating frame member, 62.

89 represents a striker arm, which is also 50 pivoted to the block, 83, or other part connected with the frame member, 62, and is normally supported by the up-turned portion, 87, of the arm, 85, in such a position as to clear the upper end of a trip arm, 90, in 55 this instance pivotally mounted upon and movable independently of the rock shaft, 63. The actuating arm, 90, is operatively connected with the stop arm, 26, herein before referred to for arresting the downward 60 movement of the lifting arm, 23, carrying the comber. The connection may be made in numerous ways, but in the present instance I have shown the trip arm, 90, secured to a sleeve, 91, on the rock shaft, 63, 65 the other end of the sleeve being provided

with an arm, 92, having an aperture in its upper end through which a draw bar, 93, extends, a spring, 94, being interposed between a nut or collar on the outer end of the rod, 93, and the arm, 92. The opposite end of the rod, 93, is pivotally connected to an arm, 95, adjustably secured to the rock shaft, 27, to which the oscillating stop arm, 26, is secured and I prefer to provide stops, 96 and 97, to limit the movements of the lever, 95, and hence the movements of the stop arm, 26. A spring, 98, connected to the lever, 95, and to the frame holds the arm, 95, normally in contact with the stop, 97, and thereby holds the stop arm, 26, in inoperative position. The sleeve, 91, is provided with a spring, 99, in this instance engaging the shaft, 52, for normally holding the trip arm, 90, in its normal position.

Having described the various parts of the apparatus herein shown, I will now describe the operation of the same.

The pile of sheets is placed upon the table, 2, and the table is raised by lifting the rack bars, 4, until the topmost sheet is in contact with the comber when the latter is in its lowest position, and into contact with the bending rod, 33. If power is applied to the driving shaft from any suitable source 95 of power the first cycles of the machine will result in merely fanning out the topmost sheets into the positions indicated in Fig. 5, and if it is desired to expedite the operation of the machine the topmost sheets above 100 the upper inner edge of the front guide, 30, may be fanned out by hand. Assuming the parts to be in the position shown in Fig. 5 the top sheet having been moved far enough forward to enable it to be engaged 105 by the separator or separators, 50, the cycle of the machine will be as follows: The separator or separators will move upwardly separating the topmost sheet, and raising it to such a point that the dividing roller, 61, may pass readily beneath the sheet. The oscillating frame member 62 is then rocked in the direction of the feed roller, 36, so as to insert the dividing roller, 61, beneath 110 the separated sheet at the same time carrying forward the clamping member, 71. I prefer to so construct the cams controlling the various parts that at this point in the cycle, the combing device will be lifted out of contact with the pile of sheets, the separator or separators will be caused to descend into contact with the second sheet of the pile and the movement of the dividing roller will be arrested or delayed until this has taken place. When the separator or separators descend, the arm, 81, will strike the lever, 76, as before described and depress the clamp, 71, upon the second sheet just 115 at or before the moment that the dividing roller, 61, presses the top sheet against the 120 sleeve, 91, on the rock shaft, 63, the other end of the sleeve being provided 125 with an arm, 92, having an aperture in its upper end through which a draw bar, 93, extends, a spring, 94, being interposed between a nut or collar on the outer end of the rod, 93, and the arm, 92. The opposite end of the rod, 93, is pivotally connected to an arm, 95, adjustably secured to the rock shaft, 27, to which the oscillating stop arm, 26, is secured and I prefer to provide stops, 96 and 97, to limit the movements of the lever, 95, and hence the movements of the stop arm, 26. A spring, 98, connected to the lever, 95, and to the frame holds the arm, 95, normally in contact with the stop, 97, and thereby holds the stop arm, 26, in inoperative position. The sleeve, 91, is provided with a spring, 99, in this instance engaging the shaft, 52, for normally holding the trip arm, 90, in its normal position.

feed roller, 36, so as to hold the second sheet against any movement, as shown in Fig. 7, while the feed roller, 36, withdraws the top sheet and passes it between the delivery 5 roller, 41, and idle roller, 46, from whence it passes out of the machine, to the printing press or other device. As soon as the feed roller, 36, has rotated far enough to deliver the top sheet the clamp, 71, is released, the 10 separator or separators begin to rise in engagement with the next sheet, now the top sheet, and the oscillating frame member, 62, recedes to its original position, while the comber again descends upon the pile 15 of sheets and feeds the top sheet forward as the separator raises its forward edge. As the oscillating frame member, 62, recedes, assuming that the sheet engaged by the separator has not been fed too far the 20 striker arm, 89, passes over the top of the trip arm without operating it, as indicated in Fig. 7. If, however, the second sheet has been fed forward too far it will engage the trigger, 82, and thereby lower the short 25 arm, 85, connected therewith, overcoming the light spring, 88, and lower the striker arm down upon the stud, 86, as indicated in Fig. 8. When the frame member 62 recedes the striker arm 89, will engage the 30 upper end of the trip arm, 90, as shown in Fig. 8, rocking said arm and through the sleeve, 91, rocking the arm, 92, and shifting the arm, 95, from stop pin, 97, to stop pin, 96, (see Fig. 2), thereby moving the stop 35 arm 26 (see Fig. 5) so as to bring its shoulder beneath the stop or shoulder 29 on the lifting arm, 23, and preventing the comber from descending during the next cycle of the machine, so that the topmost sheets will 40 not be farther advanced and as the top sheet will nevertheless be drawn off and delivered the next sheet below, when it becomes the top sheet, will not be too far in advance. If it should be, however, the 45 comber will be again held out of operation in the same manner.

It will be seen that by means of the construction herein shown and described the machine is automatically self regulating 50 and will prevent over feeding regardless of the thickness of the sheets both as to the combing operation and as to the vertical feed which is arrested simultaneously with the arresting of the descent of the comber. 55 As before stated in constructing the machine I provide that the feed shall be sufficient under any circumstances, and interrupt the feed in the manner described for the purpose of making it self regulating. 60 Obviously if the feed at any time should be insufficient it would simply mean that one or more cycles of the machine would pass without effecting the delivery of a sheet and no other result would be brought 65 about, but as a matter of fact this does not

happen in actual practice and the provision against over feeding herein shown is efficient and enables the apparatus to handle sheets of any thickness with the practical certainty of delivering a sheet at each cycle of operation of the machine. It will also be noted that the second sheet is clamped and firmly held in position adjacent to its forward edge as the separator or separators descend to their lowest position and engage the edge 70 of the said second sheet and the said second sheet is preferably held by the clamp until the comber descends into engagement with the pile, and upon said sheet which has become the topmost sheet by the delivery of 75 the sheet above it, when the clamp is released, the dividing roller retracted and the separator again actuated to raise the said sheet with which it is already in operative engagement. 80

What I claim and desire to secure by Letters Patent is:

1. In a machine for feeding sheets or like articles, the combination of means for supporting a pile of the articles to be fed, feeding mechanism located adjacent to the delivery end of said supporting means, means for lifting portions of the topmost sheet into a position to be engaged by the feeding mechanism without moving it rearwardly, 90 a clamp for engaging the second sheet adjacent to the delivery end of the pile after the first sheet has been lifted, and means for moving said clamp out of the path of the first sheet and into engagement with the 95 second sheet of the pile. 100

2. In a machine for feeding sheets or like articles, the combination of means for supporting a pile of the articles to be fed, feeding mechanism located adjacent to the delivery end of said supporting means, means for lifting portions of the topmost sheet into a position to be engaged by the feeding mechanism without moving it rearwardly, 105 a clamp for engaging the second sheet adjacent to the delivery end of the pile after the first sheet has been lifted, and means independent of said clamp for engaging the topmost sheet of the pile and preventing it from being moved rearwardly. 110

3. In a machine for feeding sheets or like articles, the combination of means for supporting a pile of the articles to be fed, a feed roller located adjacent to the delivery end of said supporting means, means for lifting portions of the topmost article into position to be engaged by the feed roller, a clamp movable longitudinally of the machine toward and from said supporting 120 means, and means for moving said clamp downwardly into operative engagement with the second sheet of the pile for holding it while the topmost sheet is delivered from the machine. 135

4. In a machine for feeding sheets or like 140

articles, the combination of means for supporting a pile of the articles to be fed, a feed roller located adjacent to the delivery end of said supporting means, a comber adapted 5 to engage the topmost sheet and feed it endwise, a separator for lifting portions of the topmost sheet, a dividing roller movable toward and from the feed roller for pressing the lifted portion of the topmost 10 sheet against the feed roller, and a clamp for engaging the second sheet of the pile and holding it while the topmost sheet is delivered.

5. In a machine for feeding sheets or like 15 articles, the combination of means for supporting a pile of the articles to be fed, a feed roller located adjacent to the delivery end of said supporting means, a comber adapted to engage the topmost sheet and feed it 20 endwise, a separator for lifting portions of the topmost sheet, a dividing roller movable toward and from the feed roller for pressing the lifted portion of the topmost sheet against the feed roller, and a clamp 25 movable with the dividing roller beneath the first sheet and above the second sheet of the pile, and means for depressing said clamp upon the second sheet to hold it while the topmost sheet is delivered from the machine.

30 6. In a machine for feeding sheets or like articles, the combination of means for supporting a pile of the articles to be fed, a feed roller located adjacent to the delivery end 35 of said supporting means; a separator for lifting portions of the topmost article, a movable frame provided with a dividing roller, movable toward and from the feed roller longitudinally of the machine, to 40 carry the dividing roller beneath the lifted portion of the topmost sheet and press it against the feed roller, a clamp carried by said frame and means for depressing the clamp into operative engagement with the 45 second sheet of the pile to hold it while the first sheet is delivered from the machine.

50 7. In a machine for feeding sheets or like articles, the combination of means for supporting a pile of the articles to be fed, a feed roller located adjacent to the delivery end of said supporting means, a separator 55 for lifting portions of the topmost article, a movable frame provided with a dividing roller, movable toward and from the feed roller longitudinally of the machine, to carry the dividing roller beneath the lifted portion of the topmost sheet and press it against the feed roller, a clamp carried by said frame, means for depressing the clamp into 60 operative engagement with the second sheet of the pile to hold it while the first sheet is delivered from the machine, and means for lowering the separator into engagement with the second sheet while it is held by said 65 clamp.

8. In a machine for feeding sheets or like 70 articles, the combination of means for supporting a pile of the articles to be fed, a feed roller located adjacent to the delivery end of said supporting means, a vertically movable separator for lifting portions of the topmost article, a comber for engaging the topmost article, means for intermittently raising and lowering said comber out of 75 and into contact with the topmost sheet of the pile, a movable dividing roller for pressing the lifted portion of the topmost sheet into engagement with the feed roller, a clamp for engaging the second sheet of the pile and holding it while the topmost sheet 80 is delivered, and means for lowering the separator into engagement with the second sheet while it is held by the said clamp.

9. In a machine for feeding sheets or like 85 articles, the combination of means for supporting a pile of the articles to be fed, feeding mechanism located adjacent to the delivery end of said supporting means, means for lifting portions of the topmost sheet into a position to be engaged by the feeding 90 mechanism without moving it rearwardly, a clamp for engaging the second sheet adjacent to the delivery end of the pile after the first sheet has been lifted, means independent of said clamp for engaging the topmost 95 sheet of the pile and preventing it from being moved rearwardly, and means for moving said clamp out of the path of the first sheet and into engagement with the second sheet of the pile.

10. In a machine for feeding sheets or 100 like articles, the combination of means for supporting a pile of the articles to be fed, a feed roller located adjacent to and above the delivery end of said supporting means, means for lifting portions of the topmost article and bringing them into operative 105 relation with the feed roller, a bending rod extending transversely above the top sheet of the pile at a distance from the end engaged by said lifting means for holding the top sheet in engagement with the pile and preventing it from slipping rearwardly, and a comber for engaging the topmost sheet of the 110 pile and feeding it beneath said bending rod.

11. In a machine for feeding sheets or like 115 articles, the combination of means for supporting a pile of the articles to be fed, a feed roller located adjacent to and above the delivery end of said supporting means, means for lifting portions of the topmost article and bringing them into operative relation with the feed roller, a bending rod extending transversely above the top sheet of the 120 pile at a distance from the end engaged by said lifting means for holding the top sheet in engagement with the pile and preventing it from slipping rearwardly, a comber for 125 engaging the topmost sheet of the pile and 130

feeding it beneath the bending rod, and means for moving the comber into and out of contact with the topmost sheet of the pile.

12. In a machine for feeding sheets or like articles, the combination of means for supporting a pile of the articles to be fed, feeding mechanism located above and adjacent to one end of said supporting means, a comber for engaging the topmost sheet of the pile, means for moving the comber into and out of engagement with the topmost sheet of the pile, means for lifting portions of the topmost sheet into position to be engaged by said feeding mechanism, and means for holding portions of the topmost sheet in engagement with the pile for preventing the rearward movement of the sheet.

13. In a machine for feeding sheets or like articles, the combination of means for supporting a pile of articles to be fed, feeding mechanism located above and adjacent to one end of said supporting means, a comber for engaging the topmost sheet of the pile, means for moving the comber into and out of engagement with the topmost sheet of the pile, means for lifting portions of the topmost sheet into position to be engaged by said feeding mechanism, means for holding portions of the topmost sheet in engagement with the pile for preventing the rearward movement of the sheet, and a clamp for engaging the second sheet of the pile beneath the lifted portion of the topmost sheet for holding said second sheet while the topmost sheet is delivered from the machine.

14. In a machine for feeding sheets or like articles, the combination of means for supporting a pile of the articles to be fed, feeding mechanism located above and adjacent to one end of said supporting means, a comber for engaging the topmost sheet of the pile, means for moving the comber into and out of engagement with the topmost sheet of the pile, means for lifting portions of the topmost sheet into position to be engaged by said feeding mechanism, means for holding portions of the topmost sheet in engagement with the pile for preventing the rearward movement of the sheet, a clamp for engaging the second sheet of the pile beneath the lifted portion of the topmost sheet and means for lowering said lifting means into engagement with the second sheet of the pile while it is held by said clamp.

15. In a machine for feeding sheets or like articles, the combination with means for supporting a pile of the articles to be fed, and a comber for fanning out the upper sheets of the pile, of an inclined feed board for supporting the projecting portions of the fanned out sheets, a feed roller located above said feed board, means for lifting the topmost sheet, a movable dividing roller for pressing the lifted portion of the topmost sheet against the feed roller, and a clamp

for clamping the second sheet of the pile upon said feed board to hold it while the topmost sheet is delivered from the machine.

16. In a machine for feeding sheets or like articles, the combination with means for supporting a pile of the articles to be fed, and a comber for fanning out the upper sheets of the pile, of an inclined feed board for supporting the projecting portions of the fanned out sheets, a feed roller located above said feed board, means for lifting the topmost sheet, means for pressing the lifted portion of the topmost sheet into engagement with the feed roller, a clamp movable longitudinally of the machine above said feed board, and means for depressing said clamp upon the second sheet of the pile to clamp it to the feed board for holding the second sheet while the topmost sheet is delivered from the machine.

17. In a machine for feeding sheets or like articles, the combination of a table for supporting a pile of sheets, a comber for fanning out the topmost sheets, a vertically disposed front guide for engaging the pile of sheets adjacent to the delivery end of the machine, an inclined feed board extending from the upper end of said front guide to support the projecting portions of the fanned out sheets of the pile, a feed roller located above said inclined feed board, a vertically movable separator extending through a guiding aperture in the feed board for lifting a portion of the topmost sheet toward the feed roller, a dividing roller adapted to pass beneath the lifted portion of the topmost sheet and press it against the feed roller, and a clamp for engaging the second sheet of the pile and clamping it upon the feed board while the topmost sheet is delivered from the machine.

18. In a machine for feeding sheets or like articles, the combination with means for supporting a pile of the articles to be fed, and means for separating and delivering the topmost article of the pile, of a comber for fanning out the uppermost sheets of the pile, means for raising said comber out of engagement with the pile during a portion of the cycle of the machine, a stop for preventing the descent of the comber into engagement with the pile, and means actuated by the second sheet of the pile, and located out of the path of the topmost sheet for bringing said stop into operative relation with the comber.

19. In a machine for feeding sheets or like articles, the combination with means for supporting a pile of the articles to be fed, and means for separating and delivering the topmost article of the pile, of a comber for fanning out the uppermost sheets of the pile, means for raising said comber out of engagement with the pile during a portion of the cycle of the machine, a stop

for preventing the descent of the comber into engagement with the pile, tripping mechanism for moving said stop into operative relation with the comber and a device 5 in the path of the second sheet of the pile and out of the path of the topmost sheet for operating said trip mechanism.

20. In a machine for feeding sheets or like articles, the combination with means for 10 supporting a pile of the articles, to be fed, and means for separating and delivering the topmost article of the pile, of a comber for fanning out the uppermost sheets of the pile, means for raising said comber out of 15 engagement with the pile during a portion of the cycle of the machine, a stop for preventing the descent of the comber into engagement with the pile, tripping mechanism for bringing said stop into operative 20 relation with the comber, a striker carried by a movable part of said separating and delivering means normally out of operative 25 relation with the tripping mechanism, and a trigger operatively connected with said striker and having a part in the path of the second sheet of the pile and out of the path of the topmost sheet, for moving said striker into operative relation with the tripping mechanism.

30 21. In a machine for feeding sheets or like articles, the combination with a supporting table, a comber for fanning out the uppermost sheets of the pile, located above said table, and means for raising said 35 comber out of operative relation with the pile of sheets on said table during a portion of the cycle of the machine, of a stop for preventing the lowering of the comber into operative engagement with the pile of 40 sheets, a tripping mechanism for said stop, a separator for raising a portion of the topmost sheet, a feed roller, a dividing roller, means for moving said dividing roller toward and from the feed roller, a striker carried 45 by the support for the dividing roller and normally held out of operative relation with said tripping mechanism, and a trigger carried by the support for the dividing roller, and having a portion in position to 50 be engaged by the second sheet of the pile if the latter is fed beyond its desired position, for moving the striker into position to engage the tripping mechanism.

22. In a machine for feeding sheets and 55 like articles, the combination with a support for a pile of sheets, a comber for fanning out the uppermost sheets of the pile, and means for lifting the comber out of opera-

tive relation with the pile during a portion of the cycle of the machine preventing the 60 descent of the comber into engagement with the pile, a feed board for supporting portions of said fanned out sheets, means for lifting portions of the topmost sheet and delivering said sheet from the machine, and 65 a trigger in the path of the second sheet of the pile and out of the path of the topmost sheet for effecting the actuation of said stop.

23. In a machine for feeding sheets and 70 like articles, the combination of the means for supporting a pile of sheets, a comber movable into and out of engagement with the topmost sheet of the pile, means for lifting portions of the topmost sheet and delivering it from the machine, and means for holding the comber out of engagement with the pile of sheets including a part in the path of the second sheet of the pile and out of the path of the topmost sheet. 80

24. In a machine for feeding sheets and like articles, the combination with a vertically movable support for a pile of sheets, a comber for engaging the topmost sheet of the pile, mechanism for feeding the said 85 movable support vertically, and mechanism for raising and lowering the comber operatively connected with said feeding means, of devices for preventing the lowering of the comber into engagement with the topmost 90 sheet of the pile, and simultaneously arresting the feed of said movable support, having a part in the path of the second sheet of the pile and out of the path of the topmost sheet, and means for raising portions 95 of the topmost sheet of the pile and delivering the topmost sheet from the machine.

25. In a machine for feeding sheets and like articles, the combination with means for supporting a pile of sheets, a comber 100 movable vertically into and out of engagement with the topmost sheet, a feed roller, a separator for lifting portions of the topmost sheet and a dividing roller adapted to pass beneath the topmost sheet and press it 105 against the feed roller, of a clamp for engaging the second sheet of the pile, normally inoperative means for holding the comber out of engagement with the pile of sheets, and a trigger in the path of the second sheet 110 of the pile and out of the path of the topmost sheet for bringing said mechanism into operation.

In testimony whereof I affix my signature.

ROBERT E. KEMPER.

It is hereby certified that in Letters Patent No. 1,180,299, granted April 25, 1916, upon the application of Robert E. Kemper, of Rensselaer, New York, for an improvement in "Sheet-Feeding Machines," an error appears in the printed specification requiring correction as follows: Page 8, line 60, claim 22, after the word "machine" insert the words *a stop for*; and that the said Letters Patent should be read with this correction therein that the same may conform to the record of the case in the Patent Office.

Signed and sealed this 30th day of May, A. D., 1916.

[SEAL.]

J. T. NEWTON,
Acting Commissioner of Patents.
